UNITED STATES PATENT OFFICE.

LAWRENCE H. MORSE, OF CLEVELAND, OHIO, ASSIGNOR TO THE AMERICAN MULTIGRAPH COMPANY, OF CLEVELAND, OHIO, A CORPORATION OF OHIO.

PRINTING PRESS.

Original application filed March 9, 1925, Serial No. 14,013. Divided and this application filed May 6, 1926. Serial No. 107,048.

This invention relates to printing presses and is more particularly concerned with presses of the bed and cylinder type, wherein the bed reciprocates. The general object is to 5 provide a very simple and efficient mechanism for maintaining proper lubricant between the traveling bed and its support.

More specifically, the invention comprises a reciprocable roller frame, mounted between 10 the stationary support and the traveling bed, and an oil carrier secured to the roller frame and adapted to dip in oil on each reciprocation and deliver it to the trackway on which the roller frame travels. The invention is 15 hereinafter more fully described, in connection with a preferred embodiment illustrated in the drawings, and the essential characteristics are summarized in the claims.

In the drawings, Fig. 1 is a vertical longitudinal section through a bed and cylinder printing press embodying my invention, the plane of the section being indicated on the line 1—1 in Fig. 3; Fig. 2 is a transverse vertical section on the line 2—2 of Fig. 1; Fig. 3 20 is a plan of the printing press, particularly broken away; Fig. 4 is a perspective of a portion of the roller frame and the oil carriers carried thereby; Fig. 5 is a detail in vertical section, of one of the oil carriers and its oiling 25 trough.

I will first describe briefly the printing press shown, and then, in detail, the oiling system and the spacing means for the rollers constituting this invention.

30 The stationary frame of the machine may be of any suitable form. It is shown as comprising a horizontal bed plate 10, depressed between side walls 11, which merge into suitable supporting legs 12. The side walls have 35 external flanges 14 on which are mounted standards 15, carrying the shaft 20 of the rotary platen 21, provided with paper grippers 22.

Formed on the upper surface of the stationary bed plate 10, are trackways for the rollers of the roller frame. Four of such trackways, as shown are designated 17. Resting on these trackways are the rollers 30 of the roller frame about to be described and 40 resting on these rollers, is a reciprocatory bed 40, carrying the type form.

The present application is a division of my co-pending application No. 14,013, filed March 9th, 1925, which has resulted in Patent No.

1,638,544, issued August 9, 1927. I will first 55 describe my novel means for positioning the rollers of the roller frame. The four rows of rollers shown are grouped in two sets, each set being mounted on a positioning member comprising a longitudinal channel-shaped 60 spacing plate 32 having down turned flanges 33, and a series of rods 35, mounted on these flanges. The rollers 30, are journaled on the projecting ends of these rods, suitable washers and pins 37 maintaining the rollers in place. 65 The stationary tracks 17 are preferably hardened horizontal strips and the flanges 38 of the spacing members extending lower than the rollers along the inner side of these strips and thus prevent lateral displacement of the roller 70 frame.

The reciprocatory type bed 40 has downwardly extending webs 41 on the underside of which are hardened strips 42, which rest on the rollers. This traveling bed is guided by 75 the lining strips 44 on the inner sides of the frame sides 11. This bed carries a suitable chase 45 between bearing strips 46, which coact with the platen roller. The bed may also have the rack 47 adapted to coact with a gear 80 25 on the platen roller.

Any suitable means may be employed to 85 reciprocate the bed 40. As shown, it is provided with a downwardly extending vertical guideway 50, rigidly secured to the underside of the bed. In this guideway, is a sliding block 51, which is secured to one length of an endless chain 52, mounted on sprockets 53 and 54, carried by the stationary frame. One of these sprockets is driven to operate the chain 90 continuously. I have shown a driving belt 60 operating on a pulley 61 which is keyed to the shaft of sprocket 53. Another belt 64, running from a pulley on this same shaft to a pulley 27 operates the platen roller 21. 95

It will be seen from the construction described that as the belt 60 travels, the sprocket chain operates the block 51 first in one direction and then gradually brings it to a stop and then carries it in opposite direction, thus reciprocating the bed 40, bringing it gradually to a stop at each end of the stroke, after the manner of the Scotch yoke. At the same time, the platen is rotated by its belt and may be maintained in proper registration with the type form by the rack and gear mentioned. Suitable eccentric mechanism, indicated at 100 28 but not shown in detail, may raise the platen 105

clear of the rack 47, so that it rotates idly on one stroke of the bed.

The above described driving mechanism, which is substantially copied from my co-pending application No. 602,161 filed November 30th, 1922, is shown simply as illustrative of any means for reciprocating the bed. When the bed is thus reciprocated, it rolls on the rollers 30, and these rollers roll on the tracks 17 of the stationary bed, so that the whole roller frame has a travel first in one direction and then in the other equal to half of the stroke of the type bed. A feature of the present invention is the means for maintaining the tracks for these rollers constantly lubricated. This will now be specifically described.

The stationary bed 10 is extended at the end of the machine and formed into two horizontal troughs 70, Figs. 1, 3 and 5. These troughs are adapted to contain lubricating oil indicated by 71, Fig. 5. On the endmost rods 35 of the roller spacers 32, are pivotally mounted sets of links 75 each adjacent pair 25 of which carry a roller 76.

At the end of the stroke, the rollers 76 occupy the pockets 70, as shown in Fig. 5, and are thus immersed in the oil. Then, as the roller frame moves, such rollers ride up on 30 the frame incline 78, Fig. 5, and thereafter travel along the trackways 17. They thus distribute oil to these trackways, which is taken up by the rollers 30 and by them distributed to the undersides of the bars of the 35 guide tracks 42 on the undersurface of the reciprocating bed.

It will be seen from Fig. 2 that the bed carries ribs 18 on its upper surface located on opposite sides of the trackways 17, parallel therewith and some distance therefrom, thus providing oil channels into which the 40 surplus oil may pass from the tracks 17 and eventually reach the pockets 70.

It will be seen that the oiling device is extremely simple. Experience has demonstrated that it is very effective in maintaining the trackways properly lubricated. The amount of oil in the pockets 70 may be readily 45 inspected, and thus replenished as necessary.

Having thus described my invention, I 50 claim:—

1. In a printing press, the combination of a substantially horizontal trackway, a reciprocating member mounted thereon, an oil carrier carried by the reciprocating member, an oil receptacle into which the oil carrier dips at each cycle of operation of the reciprocating member, said oil carrier being adapted to convey oil to the trackway supporting said 55 reciprocating member.

2. In a printing press of the bed and cylinder type, the combination with a substantially horizontal trackway and a reciprocating bed supported thereby, an upwardly 60 opening oil reservoir and reciprocating means

adapted periodically to dip into the reservoir and receive oil and automatically spread it on the trackway.

3. In a printing press of the bed and cylinder type, the combination with a trackway, a reciprocating bed, and a traveling set of rollers between the trackway and reciprocating bed, of an oil carrier member movable with said traveling set of rollers and adapted to periodically receive oil automatically consequent upon its reciprocation. 75

4. In a printing press, the combination of a support, a reciprocating type bed, a series of traveling rollers between the support and bed, an oil reservoir and an oil collecting roller movable with the set of traveling rollers along their track and adapted to dip into the reservoir upon each cycle of operation. 80

5. In a printing press, the combination of a support, a reciprocating type bed, a series of traveling rollers between the support and bed, an oil reservoir, an oil collector comprising an arm pivotally carried with the series of rollers, and a roller mounted on said arm, said last mentioned roller being adapted to 90 pass into the reservoir at one end of the stroke of the type bed and travel out of said reservoir and along the support after the type bed is moved.

6. In a printing press, the combination of a frame bed, a reciprocating type bed, two series of rollers between the frame bed and type bed, a channel-shaped member, and a series of rods mounted in the flanges of the member and extending loosely through the rollers in two series respectively, links pivoted to the channel-shaped member, rollers mounted on said links directly behind the rollers first mentioned, and an oil reservoir into which the link-carried rollers dip at the 100 end of the stroke. 95

7. In a machine of the character described, the combination of a substantially horizontal trackway, an oil receptacle adapted to contain oil below the level of the trackway in a region adjacent the end of the trackway, a reciprocating member mounted on the trackway, an oil carrier movably connected to the reciprocating member adjacent one end and adapted to drop by gravity into the receptacle at substantially the end of the stroke of said reciprocating member, said carrier being adapted to convey oil from the receptacle to the trackway on the opposite stroke of the said member. 110

8. In a machine of the character described, the combination of a substantially horizontal trackway, an oil receptacle opening upwardly, an oil carrier pivotally connected to the reciprocating member adjacent one end and adapted to rest on the trackway during the 115 working stroke of said member and adapted to drop into the oil receptacle as said member completes its stroke. 120

9. In a machine of the character described, a bed formed with an oil receptacle, said bed 125

- having a substantially horizontal trackway, there being a downward incline into the oil receptacle at the end of the trackway, a reciprocating member on said trackway, an oil carrier mounted on said reciprocating member and adapted to travel down such incline into the oil on one stroke and on the opposite stroke to travel up the incline and travel along the trackway delivering oil thereto.
10. 10. The combination of a bed having a substantial horizontal trackway and formed with an upstanding flange providing an oil receptacle opening upwardly into which the track leads by a downward incline, a reciprocable member; mechanism for reciprocating it on said trackway, the upward opening of the oil receptacle being beyond the stroke of said member, enabling the receptacle to be readily charged with oil, an oil carrier pivoted to the end portion of said reciprocating member and adapted adjacent the end of the stroke to travel down such incline into oil carried by the bed and on the opposite stroke to travel up the incline and travel along the trackway delivering oil thereto.
15. 11. In a printing press of the bed and cylinder type, the combination of a frame carrying a plurality of parallel horizontal trackways and formed with means for carrying oil, said means being open upwardly adjacent the end of the trackways to allow oil to be added, the ends of the trackways being inclined downwardly into the oil receptacle described, a reciprocating member mounted on said
- trackways, oil carriers connected to and projecting beyond the end portion of the member at each trackway, each of said oil carriers comprising a pair of arms having their inner ends pivotally engaging portions of the reciprocating member and having a cross member connected to their outer ends, said cross member being in the vertical plane of the trackway and adapted to travel down the incline by gravity as the reciprocating member approaches the end of one stroke and be drawn up the incline and travel along the trackway as the reciprocating member moves in the opposite direction.
20. 12. In a printing press of the bed and cylinder type, the combination of a frame carrying a horizontal trackway and having a receptacle for carrying oil, said receptacle being open upwardly adjacent the end of the trackway to allow oil to be added, the bed having upwardly extending ribs on opposite sides of the trackway and parallel therewith to provide oil gutters leading at the end to the receptacle, a reciprocating member mounted on said trackway, an oil carrier connected to said reciprocating member and adapted to dip into the oil as the reciprocating member approaches the end of one stroke and to travel along the trackway as the reciprocating member moves in the opposite direction.
25. 13. In testimony whereof, I hereunto affix my signature.

LAWRENCE H. MORSE.
